Isaac F Baker's
Design for ornaments for furniture

Cora Munro

D.216

Patented April 10. 1849

R. Cornelius & Co assignee of J. F. Parker, Philadelphia Pat
entee's Patent No. 216 dated April 10th - 1849
The schedule referred to in these letters Patent 1° and 2°
making parts of the same.

To all whom it may concern: We do know that Isaac C^o
Parker of the City & County of Philadelphia and State of
Pennsylvania have invented & produced a new and useful
device for ornaments & furniture called Cora-Mura; &
I do hereby declare the following to be a full clear and ex-
act description thereof, reference being had to the ac-
companying drawing

The device is more particularly intended to be formed in
metal but may be executed in any other suitable mate-
rial. When made of metal it may retain its natural
surface & colour or may be gilded, silvered, bronzed or la-
quered according to the pleasure of the manufacturer
My design having no special reference to any particular
color or material

Des. 216

2

This design represents a female human figure attired in a riding dress, the hat ornamented with a bow near the front part, and a plume extending thence to the left side; a short coat & a vest with facings & buttons are represented on the upper part of the figure; a figure's neck cloth is seen about the neck; a long flowing red in habit field, partly up in front, is marked with stripes and figures, & a riding stick is in the right hand, while the left is represented as employed in holding up the habit. Branches of trees and foliage constitute the back ground of the design, the whole being delineated in the drawing annexed.

What I claim is a new invention and design to consist by letters, & numbers, as above described design called "Coras ultimo, a & full one" partly in the drawing & known to all readers, and the use thereof for ornamental furniture, in whatever manner, or in whatever combination, it is deemed may be applied, for that purpose.

Witness,

Geo. Gillatin

P. Hackman

George E. Baker
